ARCH STRUCTURE

George S. Sarros, 1504 Forest Ave., Calumet City, Ill.

Filed Oct. 2, 1958, Ser. No. 764,918

1 Claim. (Cl. 50—61)

This invention relates to improvements in arch structures, and more particularly to arch structures used to form roofs of buildings or supports for bridges.

The primary object of this invention is to provide a novel, simple, inexpensive arch structure which can be manufactured in long span at low cost from masonry materials with minimum labor to provide a fireproof strong structure requiring support only at its ends.

A further object is to provide an arch structure of this character employing preformed concrete blocks as a part thereof, bonded with and constituting an integral part of the complete structure and constituting a form for fluent materials during casting of the structure.

A further object is to provide an arch structure of this character wherein masonry elements and concrete are used in a manner to place them under compression, and in which steel reinforcement is used only to prevent shearing of the parts.

Other objects will be apparent from the following specification.

In the drawing:

FIG. 1 is a vertical sectional view illustrating the use of my invention in the formation of the arched roof of a building, taken on line 1—1 of FIG. 2;

FIG. 2 is a fragmentary top plan view of a building roof;

FIG. 3 is a fragmentary sectional view similar to FIG. 1, illustrating a modified construction of roof arch;

FIG. 4 is an enlarged fragmentary sectional view taken on line 4—4 of FIG. 1;

FIG. 5 is an enlarged fragmentary sectional view taken on line 5—5 of FIG. 4;

FIG. 6 is a perspective view of one type of block usable with this invention;

FIG. 7 is a fragmentary view illustrating another type of block usable with this invention;

FIG. 8 is a fragmentary vertical sectional view illustrating another modified embodiment of the invention;

FIG. 9 is an enlarged fragmentary sectional view of a modified form of the invention and similar to FIG. 4.

Referring to the drawings which illustrate the preferred embodiments of the invention, the numeral 10 designates the upright or supporting walls or piers or supports of a structure, such as a building or a bridge. The supports 10 may be formed of masonry, such as cement blocks or bricks, as illustrated in FIG. 1. The supports 10 may be provided with steel structural reinforcing members, such as posts 12, arranged in pilasters 14, as illustrated in FIG. 3. The supports 10 will preferably be provided with beams 16, formed of steel or of preformed reinforced concrete, at or adjacent the upper ends thereof.

Concrete blocks or other structural members, such as blocks 18 illustrated in FIG. 6, or blocks 20 illustrated in FIG. 7, are arranged to form transverse arches bearing on or extending between the beams 16. The blocks 18 are here illustrated as provided with one or more passages 19 therethrough to reduce the weight thereof, and the body of the block is preferably substantially rectangular on all cross-sections thereof. The block shown in FIG. 7 is a solid block of generally rectangular configuration and having opposed side walls 21 thereof slightly inclined relative to each other.

During the erection of the arch, suitable supports, such as those shown in FIG. 3, may be employed to hold the

2

blocks in rows of desired arch-forming configuration. Such supports may include uprights or posts 24 which support longitudinally extending horizontal members 26 at their upper ends and which are in turn interconnected by cross-brace members 28 preferably having longitudinally curved upper surfaces. Panels 30, which are of a curvature corresponding to the curvature of the top surfaces of members 28, are supported on said members. Panels 30 will preferably be of a length to support a plurality of the transverse courses or rows of the arch-forming blocks. The blocks are laid up in desired assembly by the use of mortar therebetween. Upwardly projecting metal reinforcements 32 may be positioned between blocks at suitable intervals and secured in place by the mortar.

The blocks in each course or row are preferably arranged in canted or in inclined relation, as best seen in FIG. 4, so that one end of each block overlaps the end of an adjacent block in an adjacent course or row to produce a serrated or sawtooth arrangement perpendicular to the courses, i.e., lengthwise of the structure.

After the blocks 18 are laid up in arch-forming relation over the entire extent of the building roof or bridge arch or other structure to be formed, metal reinforcements are arranged in any suitable manner. In the construction shown, curved steel rods 34 are preferably arranged to extend across each arch in the V-groove defined between adjacent arch courses, as best seen in FIG. 4. Other reinforcing may also be provided, such as steel mesh 36, which preferably is located spaced above the contour of the uppermost parts of the blocks. Concrete is then poured over the block structure at 38 to form a monolithic coating or layer imbedding the reinforcing members, such as the members 32, 34 and 36. The concrete preferably has a smoothly arched or curved upper surface conforming to the arch arrangement of the supporting blocks. When the concrete sets, a uniform or integral structure is produced, made up in part of the concrete and the preformed blocks bonded thereto and reinforced by the metal reinforcing members. It will be observed that the concrete will have a bottom contour of corrugated or ribbed character whose ribs are curved lengthwise thereof correspondingly to the arch and are of a strong character by virtue of reinforcing members 18.

After the concrete has set, the supporting forms may be withdrawn and the structure provides a clear span of great strength wherein the concrete layer and the preformed concrete blocks are placed in compression so that they are capable of withstanding stresses exerted thereon and of maintaining the desired arch shape.

The concrete arch structure exerts a force tending to spread the walls or supports 10. It is desirable to reinforce the walls to sustain such stress. Tie rods may be used for this purpose at spaced intervals along the length of the building or other structure. Thus, as seen in FIG. 1, in a construction employing an arch of the parabolic form, the rods 40 may connect the upper end portions of the walls 10 at and above the level of the beams 16 at which the arch commences. The tie rods will preferably extend through openings in the walls 10 at pilasters 14, as illustrated in FIG. 2. Each tie rod preferably has screw-threaded end portions and is encircled by a washer or bearing plate 42 bearing against the wall and in turn providing an abutment for a nut 44 threaded on the tie rod 40.

In instances where it is not desired to have the tie rods extend through the building, they may be extended across the top of the arch, as shown at 46 in FIG. 3, bearing downwardly thereon. The end portions 48 of the tie rods extend at an angle to the top of the roof

and pass through apertures in the upstanding structural members 12 or other part of the wall spaced above the top of the adjacent portion of the roof but somewhat below the level of the crest of the roof. Tie rod end portions 48 are preferably screw-threaded to receive nuts 50 bearing against washers 52.

In short span constructions, the arrangement shown in FIG. 8 may be employed. Here the wall or support 10 carries a reinforced concrete preformed beam 53 having a beveled surface 54 and an aperture therethrough. Blocks 56 bear against the beveled face 54, and tie rod 58 extends through the aperture. The beam projects above the upper margin of beveled face 54, so that concrete layer 60 can be retained by the upper part of the beam. The arch formed in this case will be in the form of a simple curve rather than a parabolic or other complex curve.

It will be apparent from the foregoing that a strong fireproof arch structure is provided. The canting or inclination of the constituent blocks adds to the rigidity of the structure and to its strength by providing corrugations or ribs of the arch and further assists in insuring that the stresses applied thereto in the finished structure will be compressive forces. Steel members, both for reinforcement and for tying together the walls or other supports 10, are the only members placed in tension and serve principally to prevent shear. The concrete blocks serve as forms during construction but remain in place after construction as an integral part of the structure so as to reduce the amount of fluid concrete which must be handled without at the same time detracting from the advantages of a monolithic construction. It will further be apparent that, while certain types of blocks have been illustrated herein, the structure does not require the use of such blocks or of any particular type of block, so that a wide range of choice exists which may be utilized by the designer to meet special problems or conditions encountered from time to time in the field.

While preferred, it is not essential that the blocks be canted as seen in FIG. 4, and, instead, they may be arranged as shown in FIG. 9, wherein adjacent arch forming rows are offset, with the blocks having their edges transverse of the rows positioned horizontally. Thus rows 70 provide smaller arches than rows 72 which overlap the margins of the rows 70 which they span. This provides a sawtooth contour of an arch and accommodates positioning of reinforcing bars 74 above rows

70 and between rows 72, and also accommodates use of screen reinforcing at 76 within the concrete 78.

While the preferred embodiments of the invention have been illustrated and described, it is understood that changes in construction may be made within the scope of the appended claim without departing from the spirit of the invention.

I claim:

A building structure comprising a pair of spaced elongated supporting structural units and an arched structural unit spanning between and supported by said first units, said arched unit comprising a plurality of arched rows of preformed structural blocks with the blocks in each row bonded together by mortar, each row of blocks being inclined transversely of the row with a marginal surface portion of each block in said row disposed in overlapping relation to a marginal surface portion of a block in an adjacent row, the lapping marginal surface portions being bonded together by mortar whereby said block-defined arched unit has a serrated upper surface, a monolithic concrete layer covering and bonded to the upper surface of said arched unit and having interlocking engagement with the serrations thereof, and reinforcing rods imbedded in said concrete layer and extending the length of said rows, said rods being disposed within the serrations of the upper surface of said arched unit.
